His Attorney.

UNITED STATES PATENT OFFICE.

FREDERICK H. BEROLD, OF WYOMING, OHIO.

CLOSURE.

1,159,736.

Specification of Letters Patent.

Patented Nov. 9, 1915.

Application filed June 30, 1913. Serial No. 776,697.

To all whom it may concern:

Be it known that I, FREDERICK H. BEROLD, a citizen of the United States, residing at Wyoming, in the county of Hamilton and 5 State of Ohio, have invented certain new and useful Improvements in Closures, of which the following is a specification.

My invention relates to closures of flexible material, for instance paper or other 10 fibrous sheet material.

It is the object of my invention to provide a closure capable of being tightly sealed, and is especially adapted for use as a safety container or envelop which will 15 expose attempts to tamper with or open the same.

The invention will be readily understood from the following description and claims, and from the drawing, in which latter:

20 Figure 1 is a plan view of an exemplified blank from which the front and outer closing flap of my improved closure is adapted to be made, and showing the inside face of the blank having the strips of paste applied thereto. Fig. 2 is an inverted plan view of the blank for the back of my improved closure, having its creasing lines indicated thereon, the view showing the inside face of said back and having the strip of paste on the flap 25 thereof. Fig. 3 is a rear view of the blank for the back of my improved closure, showing the same provided with its folding creases, and with the strips of paste applied thereto. Fig. 4 is a perspective view of my 30 improved closure shown in assembled relation. Fig. 5 is a vertical cross-section of my improved closure, taken on the line 5—5 of Fig. 4, showing the front and back bulged, and the closing flaps pasted together. Fig. 6 is a similar view of my improved closure, showing the closing flaps folded and pasted to the body of the closure. Fig. 7 is a vertical section of my improved device, taken on a line corresponding 35 to the line 7—7 of Fig. 4, showing the closing flaps folded and pasted; and, Fig. 8 is a horizontal section of the same, taken on a line corresponding to the line 8—8 of Fig. 6.

40 50 11, 12, represent the side members of my improved device, 11 being shown as the front and 12 as the back thereof. Each of these members is preferably provided at its lateral edges and also at its bottom with

attaching flaps arranged to be lapped upon the body portions of opposite members for forming double lapping thicknesses of material and double joints at the sides and bottom of the closure. Thus 13, 13, represent side creases and 14 a bottom crease in 55 the front body-member for forming the side attaching flaps 15, 15, and the bottom attaching flap 16. Spaces 17 are located at the proximate ends of the bottom and side-flaps respectively, these spaces being shown 60 as corner-spaces, permitting ready folding of the proximate ends of the bottom and respective side-flaps upon one another at the corners of the closure, the pasted portions forming close joints at the corners. The 65 front body-member is further provided with a closing flap 18 arranged to fold at the crease 19.

The back body-member is provided with side attaching flaps 21, 21, arranged to fold 70 inwardly toward each other on the creases 22, 22, and with a bottom attaching flap 23 arranged to fold upwardly on the crease 24. Spaces 25, 25, are between the proximate 75 ends of the bottom attaching flap and the respective side attaching flaps, these spaces being shown as corner-spaces for permitting ready folding of the proximate ends of the bottom and the respective side-flaps, and the pasted portions at said corners forming close 80 joints. The back member is further provided with a closing flap 26 arranged to fold on the crease 27. The closing flap 26 is 85 preferably shorter than the closing flap 18.

For securing the body-members together, 90 the attaching flaps of one are arranged to be attached to the faces of the proximate edges of the other, and the attaching flaps of the other are arranged to be received about the joint so formed. Thus the normally outer 95 faces of the side attaching flaps 21, 21, are provided with strips of paste 31, 31, the said attaching flaps being folded inwardly on their creases 22, 22. The normally outer face of the bottom attaching flap 23 is provided with a strip of paste 33, this bottom attaching flap being arranged to fold inwardly and upwardly on the crease 24 against the proximate pasted ends of the side attaching flaps 21, 21, for uniting said 100 proximate ends and bottom attaching flap.

105 The folded attaching flaps of the back member are received against the inner face

5 of the body-portion of the front member, the paste being between said attaching flaps and said inner face, for attaching the said back member to the front member through the medium of said attaching flaps, and forming a joint for the side edges and bottom of the closure.

10 The inner faces of the side attaching flaps 15, 15, of the front body-member, in the present exemplification, are provided with strips of paste 34, 34, and bent inwardly toward each other on the creases 13, 13, upon the outer face of the body-portion of the back member, for providing the outer 15 and reinforcing joint between said back and front members at the sides of said members. The inner face of the bottom attaching flap 16 is provided with a strip of paste 35 and folded upon the outer face of the bottom of 20 the back member on the crease 14 and thereby pasted across the proximate ends of said attaching flaps 15, 15, and the lower edge of the body portion of said back member, forming an outer and reinforcing lapping joint between the body-members at the bottom thereof.

25 The proximate ends of the inturned attaching flaps form close pasted joints with the proximate portions of the closure for forming tight joints at the lower corners. The closing flaps are preferably arranged to be pasted together and also to be folded upon the body portion of said closure and be pasted thereto. For accomplishing this 30 I prefer to provide the inner face of the outer edge of the closing flap 26 of the back body-member with a strip of paste 36, this strip of paste at its ends preferably extending to the crease 27, the moistening of the 35 paste arranged for securely attaching the closing flaps 18 and 26 together for closing the closure. I prefer that both said flaps be further pasted to the body portion of the closure, for accomplishing which the outer 40 face of the outer edge of the closing flap 26 of the back body-member is provided with a strip of paste 37 which preferably extends at its ends to the crease 27 and the inner face of the outer edge of the closing 45 flap 18 of the front body-member with a strip of paste 38, which incloses the outer edge of the closing flap 26. Said closing flaps, being folded on the creases 27 and 19, are received across the upper ends of the 50 side attaching flaps 15, 15, and the outer face of the back-member of the closure for providing a secure seal for the package.

55 By my improved construction a closure is formed which is reinforced along all edges thereof, the interior of the closure being surrounded at its edges by a double seal throughout.

60 My improved device forms a tight closure, preventing leakage of contents, irrespective of how comminuted the same may be, and

preserves the flavor and aroma of the contents, and prevents deterioration and evaporation thereof.

65 My improved closure may be made of flexible material which is substantially air tight, for instance of sized or oiled material, or material having highly impervious and calendered surface.

70 My improved device insures against tampering, as the closure is double sealed throughout, and any attempt to open the same would be disclosed by the appearance of closure.

75 Having thus fully described my invention, what I claim as new and desire to secure by Letters Patent, is:

80

1. An envelop comprising a front-member and a back-member, each of said members provided with a bottom-flap at the bottom edge thereof, with a side-flap at each side-edge thereof, and with a closing-flap at the top edge thereof, said bottom-flap and side-flaps of said back-member pasted to the back-face of said front-member, said bottom-flap and side-flaps of said front-member received about the bottom edge and side edges of said back-member and pasted to the back-face of said back-member, the closing flap of said back-member being shorter than the closing-flap of said front-member, said closing flaps provided with a band of paste between their opposed faces for pasting said opposed faces together, said closing flaps arranged to be folded upon the back face of said back-member and across the proximate ends of said side-flaps of said front-member and provided with a band of paste for pasting said closing flaps in said last-named relation.

105 2. An envelop comprising a front-member and a back-member, each of said members provided with a bottom-flap at the bottom edge thereof, with a side-flap at each side edge thereof, and with a closing flap at the top edge thereof, said bottom-flap and side-flaps of said back-member pasted to the back-face of said front-member with the proximate ends of said flaps pasted one over the other, said bottom-flap and side-flaps of said front-member received about the bottom edge and side edges of said back-member and pasted to the back-face of said back-member with the proximate ends of said flaps pasted one over the other, the closing flap of said back-member being shorter than the closing-flap of said front-member, said closing flaps provided with a band of paste between their opposed faces for pasting said opposed faces together, said closing flaps arranged to be folded upon the back face of said back-member and across the proximate ends of said side-flaps of said front-member and provided with a band of paste for pasting said closing flaps in said last-named relation.

110 115 120 125 130 3. A closure of flexible material compris-

ing a front and a back connected at their bottoms and lateral edges, said front and back each provided with a closing flap, said closing flaps being inner and outer flaps when said closure is closed, and said flaps arranged to be folded toward and pasted to the body of said closure.

In testimony whereof, I have hereunto signed my name in the presence of two subscribing witnesses.

FRED H. BEROLD.
